UNITED STATES PATENT OFFICE.

CHRISTOPHER F. CODA, OF DETROIT, MICHIGAN, ASSIGNOR TO JENKS & MUIR MANUFACTURING CO., OF DETROIT, MICHIGAN, A CORPORATION OF MICHIGAN.

APPARATUS FOR FILLING CUSHION CASINGS.

Application filed August 9, 1923. Serial No. 656,620.

In the manufacture of various kinds of upholstery the cushioning or stuffing material, for instance cotton batting, has heretofore been packed in predetermined quantities in cartons or like containers and such cartons incur expense and waste. Furthermore, when stuffing or filling cushion casings and more particularly tufted, rolled, pleated or other shaped containers, the stuffing or filling material, when in strip form, has a tendency to twist when being placed in the casing or container, such twisting action delaying the filling or stuffing operation and in all probability causing one part of the casing or container to be more compact than another part. Then again, in handling cotton batting and other strip or sheet cushioning or filling material, it is somewhat difficult to evenly place the material in a cushion casing or container, and with all this in mind, I have devised means which will greatly facilitate the placing of cotton batting or a like cushioning filler in a cushion casing or like container. First, I place the cotton batting in strip form and wound or coiled formation. Next, I provide a horizontally disposed reel or revolute holder on which the coil of batting may be placed so that it may be easily and quickly unwound and portions removed from the outer convolution of the coil. Adjacent the reel or table I suspend a feeding device through which a strip of cotton extends and with a cushion casing or container adjacent the reel or table, the feeding device, containing the strip of cotton batting, can be placed in a cushion casing or container to thread the cotton batting therein. The end of the cotton batting can be held in the casing or container, the feeding device slipped therefrom along the strip of batting, the batting divided at the entrance end of the casing or container, and then the feeding device remaining on the greater part of the cotton batting is in condition to be inserted in another casing or container. Besides the mechanical construction entering into my invention, it is obvious that a method is involved by which cushioning or filling material, in strip form, may be easily and quickly placed in a casing or container, without any danger of the material twisting and with practically no waste.

My invention will be hereinafter specifically described and then claimed and reference will now be had to the drawing, wherein

Figure 1 is a perspective view of a cushion casing or container filling apparatus in accordance with my invention;

Fig. 2 is a longitudinal sectional view of the feeding device in a cushion casing or container;

Fig. 3 is a perspective view of the feeding device;

Fig. 4 is a perspective view of a coil of strip batting or other filling material, and

Fig. 5 is a side elevation of a portion of a reel or horizontal table forming part of the apparatus.

The apparatus includes a horizontally disposed reel or revolute table top, and a feeding device, both being located in proximity to a table or work bench 1 on which is placed the cushion or containers 2 that are to be filled or stuffed with material. For the purposes of understanding my invention I have shown a cushion having pleats, rolls or tufted portions adapted to be individually filled with cotton batting or a like cushioning material. In order that the cotton batting can be expeditiously handled, in large quantities, the cotton batting is placed in strip form and the strip wound to provide a coil 3 having a hollow center or core 4 to receive a spindle or upright 5 carried by a horizontally disposed reel or table top 6. This large quantity of cotton batting is in contradistinction to small quantities usually placed in cartons and it is obvious that I save considerable expense by dispensing with such cartons.

The horizontally disposed reel or table top 6 is supported by a conventional form of anti-frictional ball or roller bearings 7 on the head 8 of a tripod 9 or other form of support which will contain the reel or table top at a proper elevation relative to the table or work bench 1, and adjacent the reel is a feeding device preferably suspended by a cable 10 or any suitable suspension means. The feeding device is in the form of a hollow or tubular member 11 tapering inwardly from its inner end to its outer end so that the outer convolution of the coil 3 may be easily threaded into the inner end of

the feeding member. The outer end of the feeding member 11 has opposed side walls slotted, as at 12 providing clearance for the fingers in gripping the strip of batting in the feeding device.

- As shown, the tubular member is of substantially circular contour in cross-section, with cross-section varying as to diameter progressively from the filling to the discharge entrance of the member, the progression being in the direction to decrease the diameter toward such discharge end. The relative dimensions at the opposite ends of the member are such that the filling strip 10 is readily entered at the entrance end while such strip is constricted at the discharge end, the taper of the member—which is in substantially a straight line—having the tendency to change the cross-sectional contour 15 of the strip from the comparatively flat form shown in Fig. 4 to a more or less circular form at the discharge end of the member, as shown in Fig. 1. This will be understood from the fact that the wall of a cross-section of the member is curved so that the decreasing dimension of the member as the strip advances causes the wall to act 20 as a guide to change the cross-sectional strip accordingly.
- 25 The advantage of this arrangement will be readily understood. The member is itself introduced into the cushion pocket, and therefore occupies space therein; and since the filling strip is located within the member—30 and therefore of less cross-sectional dimensions—such strip would not, if retaining the shape of the discharge end of the tube, fill the pocket. By changing the cross-sectional contour of the strip to the more or less circular contour, without changing the thickness dimensions of the strip itself, the strip, when 35 released from the member within the pocket, will tend to resume its flattened form, and hence the constricted circular form is changed 40 through the opening out of the strip to the extent permitted by the pocket walls. To obtain this advantage with respect to the action after the member is withdrawn, requires that the strip should be prepared for 45 this action while within the member itself. To attempt to produce this prepared effect at the entrance of the tube would require more or less careful manipulation at the entrance end of the member if the latter be of 50 uniform cross-section; in addition, the resistance to movement of the strip through the member by the friction between strip and member would tend to cause the strip to be withdrawn with the member unless 55 materially heavier pressure be employed at the projected end of the filling. By the tapered arrangement of the member, the filling is readily entered and the maximum friction is limited to a relatively small length 60 of the member; in addition, the change in 65

strip configuration takes place within the member so that the change is uniform throughout the strip under the conditions of the relative movement between member and strip.

In practice, the strip of batting is held within the feeding device and the feeding device inserted in the cushion casing or container, until it is entirely or partially therein, as shown in Fig. 2. Then the strip of batting is gripped, through the casing or container, at the slotted outer end of the feeding device and while the strip of batting is retained in the casing or container, the feeding device is slipped therefrom along the end convolution or unwound portion of the coil. Then the strip of batting is severed at the open end of the casing or container and the apparatus is in condition for filling the next casing or container. In some instances it may not be necessary to place the feeding device entirely within the casing or container. If so, the suspension cable 10 may be loose on the feeding device so as to shift to the outer end of the feeding device as it is inserted in a casing or container. Then again, the cable 10 may be of sufficient length to enter the casing or container, with the feeding device, when entirely placed therein.

It is obvious that when the tubular member 11 is being withdrawn from the casing or pocket, the contact of wall and strip, produces the change in contour of the strip progressively, due to the relative movement of member and strip, so that the released portion of the charge has the temporarily changed contour characteristic that is set up by such relative movement. Since the change is more or less temporary in character, the release of the charge from the member, permits the material of the charge to tend to return to the strip form; this can, of course, continue until the wall of the casing or pocket sets up the resistance to further change in this direction, the result being that the material has become accommodated to the shape of the pocket which receives it. The amount of change depends of course on the relative dimensions of the pocket cross-sectional area, and the area of the released charge.

It is thought that the manner of using the apparatus and the method involved will be apparent without further description, and while in the drawing there is illustrated a preferred embodiment of my invention, I would have it understood that the structural elements are susceptible to such changes as are permissible by the appended claims.

What I claim is:—

1. A mattress or cushion filler comprising an elongated hollow tube of constant dimensions open at both ends and tapered in a substantially straight line from one end to the

other, the larger end readily admitting the filler strip and the smaller end constricting the same.

2. A mattress or cushion filler comprising
5 an elongated hollow tube of constant dimensions and of substantially circular cross-section and open at both ends, said tube being tapered in a substantially straight line from one end to the other, the larger end readily admitting the filler strip and the smaller end
10 constricting the same.

3. A mattress or cushion filler comprising

an elongated hollow tube of constant dimensions and of substantially circular cross-section and open at both ends, said tube being 15 tapered in a substantially straight line from one end to the other, the larger end readily admitting the filler strip and the smaller end constricting the same, said tube being notched at its smaller end to permit grasping of the constricted portion of the tube content while the latter is within the tube. 20

In testimony whereof I affix my signature.

CHRISTOPHER F. CODA.
